UNITED STATES PATENT OFFICE.

DAVID GESTETNER, OF LONDON, ENGLAND, ASSIGNOR TO D. GESTETNER, LIMITED, OF LONDON, ENGLAND.

DUPLICATING.

No Drawing. Application filed May 25, 1925, Serial No. 32,840, and in Great Britain July 11, 1924.

This invention relates to duplicating by the employment of flexible stencils such, for instance, as may be formed by stencilizing by pressure so-called stencil sheets or by 5 photographic means.

By the employment of stencils in duplicating matter in manuscript or type, drawings, photographic prints and the like, inconvenience is often experienced in consequence of an excessive quantity of ink passing through the openings in the stencil. Not only in such case is the ink liable to offset and to run or spread, but further the consumption of ink is unnecessarily great.

15 These inconveniences are of course greater or more pronounced where the openings in the stencil are of considerable size.

In the specification of my British Letters Patent No. 148,626 I have described methods 20 of breaking up the stencil at the portions corresponding with what would normally be the solidly inked portions of the reproduction by providing in the stencil at such portions ink impermeable elements in the form 25 of lines, dots or reticulations. The ink resisting elements in a stencil produced by photographic means may, as I have indicated, be formed by exposing a suitable light sensitive pellicle to the action of light in 30 order to form thereon a positive or a negative image of a screen which is provided with lines, dots or reticulations and then again exposing the light sensitive pellicle to the action of light under conditions adapted 35 to form thereon an image of the matter to be reproduced.

In this way a stencil is formed which it- 40 self is provided with elements resisting the passage of ink at those portions of the stencil which would normally freely permit ink to pass through.

The present invention is based upon the 45 observation that a similar result can be secured by arranging behind or in front of the stencil layer of a stencil of the normal character when in use, a sheet which is pro- 50 vided at suitable intervals with elements adapted to resist the passage of ink. Normally these elements will be closely spaced and will constitute lines, dots or reticulations.

The invention comprises broadly the improvement in duplicating based upon this observation.

The invention also consists in a sheet 55 adapted to be arranged in association with the stencil in the manner above indicated, formed of porous flexible material furnished at intervals with ink resisting elements constituting, for instance, a series of lines, dots, reticulations or the like.

60 The invention further consists in the combination of a stencil or a sheet adapted to be stencilized by pressure or otherwise and a sheet of porous flexible material furnished at intervals with ink resisting elements.

65 A sheet of the character in question may comprise a sheet of porous material such as a felted or woven network of filaments and provided with ink resisting elements of the character above indicated.

70 The sheet material used may be fine lawn or other woven fabric of sufficiently fine texture or it may be a sheet of suitable porous paper such as yoshino paper.

75 The ink resisting elements may be formed on the sheet by photographic means; thus, for instance, the sheet may be coated with a layer of a light sensitive material which by exposure to the action of light will be changed in respect to its solubility in certain 80 solvents used as developers in order to form a plurality of ink impermeable lines, dots or reticulations. For instance, the sheet of porous material may be coated with bichromated gelatine and the sheet exposed to the 85 action of light behind a lined, dotted or reticulated transparency, and after such exposure the sheet treated in order to remove the portions of the light sensitive composition which have not been rendered insoluble.

90 Alternatively, a similar representation of a lined, dotted or reticulated subject may be formed by the action of light on a pellicle of bichromated gelatine or an equivalent light sensitive composition supported upon 95 a suitable backing or support from which it is transferred to a temporary support for development, the developed image being then transferred to the sheet of porous material.

100 A variety of other methods of forming the

sheet provided with the ink resisting lines, dots and reticulations may be adopted; for instance, a sheet of a suitable porous material may be subjected to a printing operation by the employment of engraved rollers by which a suitable ink resisting medium may be applied to the porous material.

A combination stencil sheet in accordance with the invention including a stencil or a sheet adapted to be stencilized by pressure or otherwise and a sheet of porous material furnished at intervals with ink resisting elements may have the two sheets secured together and, if desired, to a backing sheet or protector sheet or both in any convenient manner.

The invention also extends to a stencil sheet comprising a porous support provided at intervals over the whole of its surface with ink resisting elements in the form of lines, dots or reticulations and also with a coating of a composition adapted to be stencilized by pressure.

Thus, in accordance with this phase of the invention a sheet of yoshino paper may be subjected to treatment in the manner specified above in order to provide it with lines, dots or reticulations of ink resisting material and the sheet thus obtained may then be coated with a composition such, for instance, as one including a gelatinizing organic colloid and a tempering or softening agent enabling the composition to be stencilized by pressure.

Not only is the arrangement of a sheet provided at intervals over the whole of its surface with ink resisting elements behind a stencil which is not itself provided with ink resisting elements at the portions corresponding with what would normally be the solidly inked portions of the reproduction attended with desirable results, but the arrangement in like manner of such a sheet behind a stencil produced by photographic means as claimed in the specification of United States Patent No. 1,456,794 or a stencil formed on a sheet as described in the preceding paragraph enables impressions of an improved appearance to be secured and, further, results in a reduction in the amount of ink used.

In some cases it may be desirable to subject the yoshino paper to treatment in known manner in order to strengthen it or render it more resistant to the destructive agencies to which it is submitted in the process of manufacture; for instance, the sheet may be lightly sized with a water insoluble sizing agent.

Alternatively, the paper may be treated in order to prevent the composition forming the coating which is adapted to be stencilized soaking into its substance.

In conclusion it is pointed out that it is customary to arrange a stencil for use in

duplicating on a pad which is saturated with ink or to secure the stencil to a flexible carrier of silk gauze or the like and in some cases to arrange between the pad or gauze carrier a sheet of yoshino or like paper. The action which the pad, gauze or paper has in such conditions on the passage of ink through the stencil is rather in the direction of equalizing the delivery of the ink therethrough to secure what may be considered a normal degree of inking of the impression receiving surface, whereas a screen or sheet according to the present invention definitely reduces the quantity of ink transferred to the impression receiving surface and will be arranged between the stencil and the pad or the stencil carrier to effect this result.

Having now described my invention what I claim as new and desire to secure by Letters Patent is:—

1. The improvement in duplicating by the employment of flexible stencils, which comprises providing ink-resisting elements, suitably spaced apart, over an area co-extensive with the area of the stencil layer.

2. The improvement in duplicating by the employment of flexible stencils, which comprises arranging in association with the stencil layer of a stencil of the normal character, when in use, a sheet which is provided at suitable intervals with elements adapted to resist the passage of ink.

3. The improvement in duplicating by the aid of flexible stencils, which comprises arranging in association with the stencil layer of a stencil of the normal character, when in use, a sheet of porous flexible material furnished at intervals with ink-resisting elements constituting a series of lines.

4. For use in duplicating with the aid of stencils, a sheet adapted to be arranged in association with the stencil, formed of porous flexible material furnished at uniform intervals over the whole of its surface with ink-resisting elements.

5. For use in duplicating with the aid of stencils, a sheet adapted to be arranged in association with the stencil, formed of porous flexible material furnished at uniform intervals over the whole of its surface with ink-resisting elements constituting a series of lines.

6. For use in duplicating with the aid of stencils, the combination of a sheet adapted to be stencilized by pressure and a sheet of porous flexible material furnished at intervals with ink-resisting elements.

7. For use in duplicating, a sheet comprising a sheet of yoshino paper and provided with ink-resisting elements constituting a series of lines uniformly disposed over the whole of its surface.

8. A combination stencil sheet including a sheet adapted to be stencilized by pressure

and a sheet of porous material furnished at intervals with ink-resisting elements, the two said sheets being secured together.

9. A combination stencil sheet including a sheet adapted to be stencilized by pressure and a sheet of porous material furnished at intervals with ink-resisting elements, the two said sheets being secured together and secured to a backing sheet.

10. A combination stencil sheet including

a sheet adapted to be stencilized by pressure and a sheet of porous material furnished at intervals with ink-resisting elements, the two said sheets being secured together and secured to a backing sheet and a protector sheet.

In testimony whereof I have signed my name to this specification.

DAVID GESTETNER.
